(57) **CLAIM**

The ornamental design for the fin for a water sport device, as shown and described.

DESCRIPTION

FIG. 1 is a perspective rear view of the fin for a water sport device, which embodies my design;

FIG. 2 is a perspective front view thereof;

FIG. 3 is a side view thereof;

FIG. 4 is a side view thereof;

FIG. 5 is a top view thereof;

FIG. 6 is a bottom view thereof;

FIG. 7 is a rear view thereof; and,

FIG. 8 is a front view thereof.

The broken line portion is included for the purpose of illustrating portions of the article which form no part of the claimed design.

1 Claim, 5 Drawing Sheets
